UNITED STATES PATENT OFFICE.

JAMES V. THOMPSON, OF NEW HAVEN, CONNECTICUT.

CLOTHES-RACK.

1,219,885.

Specification of Letters Patent. Patented Mar. 20, 1917.

Application filed June 2, 1916. Serial No. 101,241.

To all whom it may concern:

Be it known that I, JAMES V. THOMPSON, a citizen of the United States, residing at New Haven, in the county of New Haven 5 and State of Connecticut, have invented a new and useful Improvement in Clothes-Racks; and I do hereby declare the following, when taken in connection with the accompanying drawings and the characters of 10 reference marked thereon, to be a full, clear, and exact description of the same, and which said drawings constitute part of this application, and represent, in—

Figure 1 a face view of a clothes rack constructed in accordance with my invention, and indicated as attached to a hot water boiler.

Fig. 2 a top or plan view.

Fig. 3 a broken rear view of one of the 20 straps illustrating means for connecting the ends.

This invention relates to an improvement in clothes racks, and while adapted to be connected with various forms of support, is particularly adapted to be applied around a hot water boiler, the object of the invention being a simple arrangement of parts which will provide a rigid support for a clothes rack; and the invention consists in the construction hereinafter described and particularly recited in the claims.

In carrying out my invention, I employ two straps 4 and 5 adapted to be secured to a boiler 6 or other support in any desired 35 manner. As herein shown, the ends of the straps are formed with eyes 7 and 8 through which the other ends 9 and 10 of the straps extend, the ends 9 and 10 being threaded for the reception of nuts 11 and 12. The 40 rack-supporting hooks are formed from wires doubled upon themselves, the doubled end 13 bent to form a hook from which the wires extend upward over the strap 4 and between that strap and the support 6, thence 45 downward, and the ends formed with eyes 14 through which the strap 5 passes. The

clothes bars 15 are also formed from wire doubled at the center and the ends formed with eyes 16 which are located between the eyes 14 and through which the straps 5 pass 50 so as to hinge the clothes bars to the lower strap. The position of the hooks 13 is such that when the clothes bars 15 are in a horizontal position, they will rest in the hooks 13 and be supported thereby. When disengaged from the hooks they will drop down into a substantially vertical position. As many hooks and bars may be employed as the size of the boiler or the needs of the user may require. The hooks, bars and straps 60 are readily formed from wire and can be readily assembled, and conveniently packed for shipment; and when in place provide a rigid rack.

I claim:—

1. A clothes rack comprising two straps adapted to be secured in place, a bar-support formed from wire having an eye through which one of the straps passes, said support extending upward inside and over the other 70 strap and downward and outward therefrom, said support terminating in a hook at its outer end, combined with a bar formed with an eye through which the lower strap passes, said bar adapted to engage with said 75 hook whereby it is supported in a horizontal position.

2. A clothes rack comprising an upper strap and a lower strap, means for connecting the ends of said straps, a support formed 80 from wire doubled upon itself and formed with eyes at the ends of the wire through which the lower strap passes, said support extending upward inside and over the upper strap and downward and outward therefrom, 85 and terminating with a hook, a clothes-bar formed from wire doubled upon itself the ends formed with eyes through which the lower strap passes, said bar adapted to be engaged with said hook whereby it is supported in a horizontal position.

JAMES V. THOMPSON.
